HEEL-SEAT FORMING MACHINE

Adolf Sanchioni, Boston, Mass., assignor to
United Shoe Machinery Corporation, Paterson, N. J., a corporation of New Jersey

Application July 29, 1935, Serial No. 33,650

3 Claims. (Cl. 12—31.5)

This invention relates to the manufacture of shoes and is illustrated as embodied in a heel-seat fitting machine.

It is an object of the invention to provide a simple machine for quickly and effectively reducing the heel-seat portions of unattached soles and forming heel-breast receiving shoulders upon the soles.

The various features of the invention will be understood and appreciated from the following detailed description read in connection with the accompanying drawings, in which—

Figure 1 is a view in front elevation of part of a punch press provided with a cutting die and a sole support in accordance with my invention; Fig. 2 is a sectional view taken along the line 2—2 of Fig. 5;

Fig. 3 is a view in perspective of the cutting die; Fig. 4 is a view in perspective of a sole provided with a heel seat and beveled shoulders in accordance with my invention;

Fig. 5 is a view in sectional elevation taken along the line 5—5 of Fig. 6, the cutting die being shown in section in proper position so as to bring out the relationship of the parts;

Fig. 6 is a view in front elevation of the sole support; and

Fig. 7 is a view in rear elevation of the sole support.

The illustrated embodiment of the present invention employs a reciprocating mechanism which may conveniently be a punch press, preferably a power operated one. Since the construction and operation of punch presses are well understood, it is deemed sufficient to point out that one general type comprises fundamentally a bed 10 (Fig. 1) and a head or frame 11 along which a ram or plunger 12 reciprocates vertically, being constrained to such movement in a predetermined path by means of suitable guides 13. The plunger 12 may be actuated from a power source through a one-cycle clutch, neither of which it is deemed necessary to show.

Secured to the plunger 12 by some suitable means is a die block 14 for supporting a cutting die 15 (Figs. 1, 3, and 5). The die is provided with a base 16 and along one edge thereof with a flange 17 which may be fastened by means of studs 18 to the die block 14 to hold the die securely in place with the base 16 horizontal. The cutting edge of the die lies in a plane, and is inclined at an angle of preferably 45 degrees from the plane of the base 16, as shown in Figs. 1 and 5. With this construction the die reciprocates ver-

tically with the cutting edge thereof inclined to the path of reciprocation.

Referring to Fig. 3, the cutting edge of the die 15 comprises a loop portion 19 having an open end and two straight edge portions 20 one at each end of the loop. The loop 19 has the shape desired to be given the heel seat of the sole, and is narrower than the width of the heel portion of the sole. The straight edges 20 are of sufficient length so that their free ends extend beyond the sides of the heel portions of soles of different sizes. With this construction, when the die 15 is driven through a properly mounted sole 21 (as will be explained hereinafter) the die removes from the sole a horseshoe-shaped piece 22 (Fig. 6) leaving a rearwardly extending heel seat or tongue 23 (Figs. 4 and 6) and at opposite sides thereof at the shank of the sole beveled shoulders 24.

In order to position the sole properly so that the die 15 can form the heel seat 23 and the beveled shoulders 24, the present invention contemplates the use of a support underlying the path of operation of the die 15 and provided with a sole engaging face at an inclination like that of the cutting edge of the die. To this end there is provided a flat heavy bed plate 25 (Figs. 1, 5, 6, and 7) adapted to rest on the bed 10 of the punch press and be secured there by any suitable means. In case the bed of the press has a slide arrangement the under face of the bed plate 25 may be provided with a channel 26. Secured to the upper face of the bed plate 25 in an upright position is a heavy plate 27 extending laterally across the bed plate as shown in Fig. 7 and provided with a squared off top as shown in Fig. 5.

The bed plate 25 and the upright plate 27 serve to support a heavy sole supporting plate or table 28 (Fig. 5) in an inclined position. To this end the lower end of the plate 28 is slabbed off at an angle of 45 degrees, and at a suitable distance therefrom the rear face of the plate 28 is provided with a 90 degree notch adapted to embrace the top and adjacent portion of the front face of the upstanding plate 27. Pins 29 are preferably mounted at the front end of the bed plate 25 and project thereabove in engagement with the front edge of the lower end of the plate 28. The plate 28 may be secured in its inclined position by studs 30 (only one shown) which extend upwardly through the bed plate 25 and into the slabbed off end of the plate 28, and by studs 31 which extend through the upper portion of the upright plate 27 and into the rear of the plate 28.

As indicated in Figs. 1 and 5, the construction so far described is secured to the bed 10 of the press so that the die 15 overlies the plate 28 more or less centrally, and with the outer face of the plate 28 and the cutting edge of the die in inclined parallel planes. Mounted centrally and removably on the outer face of the plate 28 is a brass striker plate 32 for receiving the impact of the die. Since the striker plate 32 has appreciable thickness, below the striker plate 32 (Figs. 5 and 6) the plate 28 is provided with a facing plate 33 of the thickness of the striker plate. As indicated in Figs. 5 and 6, the striker plate 32 and the facing plate 33 form the immediate support for the heel portion of the sole 21.

Since the die 15 reciprocates in a predetermined path and since the inclined plate 28 has a fixed position with respect to that path, the present invention contemplates the provision of means for varying the position of the sole on the plate 28 so that the die can operate equally well upon soles of different lengths. Stated in another way, in order that soles of different lengths can all have heel seats formed thereon by the die 15, means are provided for gaging the position of the different supported soles with respect to the die. To this end the front face of the inclined plate 28 is provided with a narrow channel 34 (Figs. 2, 6, and 7) extending from the top of the plate to a point near its bottom. At its lower end the channel 34 is both widened and deepened as indicated in Figs. 5 and 6 to form a chamber 35 extending to the slabbed off bottom of the plate 28. Beneath the chamber 35 the bed plate 25 is provided with an opening 36, and the facing plate 33, as shown in Fig. 6, is provided with a slot 37 which is preferably wider than the chamber 35 and exposes both it and portions of the plate 28 adjacent the chamber 35.

Mounted in the channel 34 is a shaft 38 the upper end of which extends beyond the top of the inclined plate 28 and is provided with a knob 39. The lower portion of the shaft 38 is threaded and extends downwardly to a point adjacent the top of the bed plate 25, preferably being located partially in the bed plate opening 36 as shown in Fig. 6. The shaft 38 underlies the striker plate 32 and the facing plate 33 and is provided intermediate its ends with a peripheral groove 40 (Figs. 5 and 6). A pin 41 extending slightly into the channel 34 so as to be received by the groove 40 prevents longitudinal movement of the shaft 38 while permitting its rotation.

Threaded to the lower end of the shaft 38 is an abutment 42 for the heel end of the sole. Referring to Figs. 5 and 6, this abutment comprises a body portion 43 adapted to fit in the chamber 35 and slide in engagement with the side walls thereof, a flat surfaced portion 44 wider than the body 43 and adapted to slide in the slot 37 in the facing plate 33 and move over the portions of the inclined plate 28 exposed thereby, and a wall 45 projecting outwardly from the flat surfaced portion 44 and against which the heel end of the sole rests. The rear face of the wall 45 is concave as shown in Figs. 5 and 6 so that it conforms generally to the curvature of the heel end of the sole. With this construction it will be seen that the abutment 42 may be caused to move up or down along the shaft 38, thereby shifting the position of a sole resting against it so that the sole may be properly positioned longitudinally with respect to the die 15.

In order to provide an indicator for the proper

position of the abutment 42 for a sole of a given length, the top of the inclined plate 28 is provided with a gage plate 46 having gage lines or indicia 47 and extending upwardly and rearwardly in a plane cutting the axis of the shaft 38. Beneath the knob 39 the shaft is threaded to receive a pointer 48, the free end of which is yoked to embrace the opposite sides of the gage plate 46. With this construction, rotation of the shaft 38 causes both the pointer 48 and the abutment 42 to move, and by coordinating the abutment 42 with the gage lines 47 in assembling the support the operative can tell at a glance where to set the abutment for a sole of any given length. Since the shaft 38 extends beyond the top of the inclined plate 28, it will be seen that when the sole is positioned on the support (Figs. 1 and 5), the forepart of the sole may engage the knob 39 and be supported thereby.

In order to insure that the sole is properly positioned laterally with respect to the die 15, the upper portion of the inclined plate 28 is provided at its sides with rearwardly extending ears 49 which serve to journal a shaft 50 provided with a knob 51. Referring to Fig. 7, between the ears 49 the shaft 50 is provided with a right hand threaded portion 52 and a left hand threaded portion 53. Each of these oppositely threaded portions receives a collar 54 from which a pin 55 projects, each pin passing through an elongated opening 56 formed therefor in the inclined plate 28 near the top thereof. These pins are long enough to engage the opposite sides of the shank portion of a sole, and by turning the knob 51, soles of varying widths can be thus engaged laterally. By properly threading the collars 54 on the threaded portions 52 and 53 when the support is assembled, it will be seen that as the knob 51 is turned, the pins 55 always move equal distances towards or from the center of the inclined plate 28, thereby relieving the operative of gaging the sole laterally with his eye and insuring that regardless of the width of the sole, the lateral gaging thereof will always be accurate.

Referring now to Fig. 5, it will be seen that by reason of the plate 28 and the cutting edge of the die 15 lying in inclined parallel planes, when the straight edge portions 20 of the cutting edge of the die strike the supported sole 21, the shoulders 24 (Fig. 4) formed thereby will extend rearwardly of the sole as they approach the flesh or upper side of the sole. In the same way, the end of the tongue 23 will be beveled also since the closed end of the loop portion 19 of the cutting edge cuts the sole more or less transversely. This permits the end of the tongue 23 to conform to the upward rise in the concavity at the rear of the top of the heel. The sides of the tongue 23 will not be beveled, but this is of no moment.

In view of the above description, little more need be said of the manner of operation of the illustrated embodiment of the present invention. The knob 39 may be set to gage the abutment 42 for a sole of a given length either before or after the sole is mounted with its heel end engaging the wall 45. Thereafter the knob 51 is turned to cause the pins 55 to engage the shank of the sole to gage it laterally. The forepart of the sole extends over the shaft 38 and the knob 39, and the operative holds the breast flap 57 out of the path of the cutting die 15, as indicated in Fig. 5. The plunger 12 of the press is actuated, whereupon the die 15 descends and simulta-

neously cuts away the margin 22 of the heel portion of the sole to provide the heel seat 23 thereon and form the shoulders 24 the beveled surfaces of which are adapted to engage the 5 breast edge of the top of the heel in the finished shoe.

Nothing herein explained is to be interpreted as limiting the invention in the scope of its application to use in connection with the particular 10 apparatus or the particular mode of operation or both selected for purposes of illustration and explanation. While the particulars of construction herein set forth are well suited to one mechanical form of the invention, it is not limited 15 to these details of construction, nor to the conjoint use of all its features, nor is it to be understood that these particulars are essential since they may be variously modified within the 20 skill of the artisan without departing from the true scope of the actual invention, characterizing features of which are set forth in the following claims.

What is claimed as new, is:

1. In a heel-seat fitting machine, a table having 25 a face for supporting the heel-seat portion of a sole, a die having a U-shaped cutting edge and a pair of edges which extend laterally of said U-shaped edge at its respective ends, and means for moving the die in a rectilinear path extending toward and rearwardly of the heel-seat portion of the sole upon said face to reduce the heel-seat portion and to form a pair of heel-breast receiving shoulders upon the same.

2. In a heel-seat fitting machine, a table for supporting the heel-seat portion of a sole, gages for positioning the heel end of the sole upon the table, a die having a U-shaped cutting edge for reducing the heel-seat portion of the sole and 5 having a pair of shoulder-forming edges which are angularly disposed to the respective ends of the U-shaped cutting edge, and means for moving the die in a rectilinear path inclined to the surface of the table and extending toward and 10 rearwardly of the heel-seat portion of the sole supported by said table to reduce the heel-seat portion of the sole and to form upon the same a pair of heel-breast receiving shoulders which are inclined lengthwise of the sole. 15

3. In a heel-seat fitting machine, a table having a flat face for supporting a sole, gages for positioning the heel end of the sole lengthwise and widthwise upon the table, a die mounted for movement in a path inclined to said face of the 20 table, said die having a U-shaped cutting edge and a pair of edges which form abrupt angles with the respective ends of the U-shaped cutting edge, and means for operating the die in 25 said path to reduce the heel-seat portion of the sole for the reception of a heel and to form upon the sole heel-breast receiving shoulders which are inclined lengthwise of the sole, the cutting edges of the die being disposed in a plane which is substantially parallel to the sole-supporting 30 face of the table as the die moves in said path.

ADOLF SANCHIONI.
